(57) **CLAIM**

The ornamental design for a face washing brush, as shown and described.

DESCRIPTION

FIG. 1 is a side view of a face washing brush, in accordance with the present invention;

FIG. 2 is a front view thereof;

FIG. 3 is a rear view thereof;

FIG. 4 is a perspective view thereof; and,

FIG. 5 is a top view thereof.

The broken lines showing the handle of the brush in FIGS. 1-5 form no part of the claimed design.
